DESIGN FOR AN OARLOCK SOCKET

Ralph E. Curry, Flint, Mich.

Application May 23, 1944, Serial No. 113,719

Term of patent 7 years

(Cl. D71—1)

To all whom it may concern:

Be it known that I, Ralph E. Curry, a citizen of the United States, residing at Flint, in the county of Genesee and State of Michigan, have invented a new, original, and ornamental Design for an Oarlock Socket, of which the following is a specification, reference being made to the accompanying drawing, forming part thereof.

In the drawing:

Fig. 1 is a front elevational view of an oarlock socket showing my new design;

Fig. 2 is a top plan view thereof; and

Fig. 3 is an end elevational view thereof.

I claim:

The ornamental design for an oarlock socket, as shown.

RALPH E. CURRY.
